C. A. LINDBERG

ADJUSTABLE SUPPORT

Filed Oct. 1, 1920

Attorneys

UNITED STATES PATENT OFFICE.

CHARLES A. LINDBERG, OF STURGIS, MICHIGAN, ASSIGNOR TO STURGIS STEEL GO-CART COMPANY, OF STURGIS, MICHIGAN.

ADJUSTABLE SUPPORT.

Application filed October 1, 1920. Serial No. 414,098.

To all whom it may concern:

Be it known that I, CHARLES A. LINDBERG, a citizen of the United States, residing at Sturgis, county of St. Joseph, State of Michigan, have invented certain new and useful Improvements in Adjustable Supports, of which the following is a specification.

This invention relates to improvements in adjustable supports.

The main objects of this invention are,

First, to provide an improved adjustable support for carriage tops or hoods of children's carriages, windshields and the like, which is very easily operated and at the same time is very secure, and

Second, to provide an improved adjustable support for carriage tops, windshields and the like, in which the parts are simple and economical to produce.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this specification, in which:

Fig. I is a detail side elevation of a structure embodying the features of my invention as applied to a child's carriage, portions only of the side of the carriage body and top being illustrated.

Fig. II is an inside view with the adjustable bracket member broken away.

Fig. III is a detail section on a line corresponding to line 3—3 of Figs. I and II, with parts shown in full lines.

Fig. IV is a detail section on a line corresponding to the broken line 4—4 of Figs. I and II, with parts in full lines.

Fig. V is an inside view corresponding to that of Fig. II showing a step in the assembling operation.

In the drawing similar reference characters refer to similar parts throughout the

several views, and the sectional views are taken looking in the direction of the little arrows at the ends of the section lines.

Referring to the drawings, 1 represents the side of the body of a child's carriage and 2 the top. The body member or supporting plate 3 in the embodiment illustrated is formed as a stamping and has attaching ears 4 offset rearwardly therefrom to receive the attaching bolts 5. The adjustable bracket member 6 is forked to receive the top bows.

The supporting plate is provided with a pair of hook lugs 7 on its rear side and a forwardly projecting pivot stud 8 for the bracket member 6 on its front side. The edge of the stud 8 is spun over the bracket member as a means for retaining the same.

The bracket member has a series of holes 9 disposed concentrically of the stud. The supporting plate has a hole 10 therein with which the holes 9 may be aligned by the adjustment of the bracket member.

The supporting plate is also provided with the stops 11 which limit the movement of the bracket member. The face plate 12 is arranged on the front side of the bracket member covering the holes 9 and providing a finish for the bracket member. The face plate has a hole 13 aligned with the hollow stud to receive the locking dog 14.

This locking dog is mounted on the disk 15 which is shaped so that it may be placed between the lugs 7 and engaged therewith by a rotative movement of the disk, the disk being notched at 16 to receive a tool facilitating its rotation and provided with a stop 17 limiting its rotation. After the disk is engaged with the lugs, the point 18 of the disk is bent upwardly to prevent its disengagement, see Fig. II.

The dog 14 is provided with a cap-like finger piece 19 disposed through the holes 13 in the face plate. A coiled spring 20 is arranged between the cap and the disk 15 to hold the dog yieldingly in engaging position. A lug 21 is struck up from the dog to retain the dog in its assembled relation on its supporting disk. The dog has a return

bend 22 providing a detent 23 adapted to pass through the hole 10 in the supporting plate and to engage the hole 9 of the bracket member aligned therewith, thus holding the 5 bracket member in its adjusted position.

With the parts thus arranged, they are quite simple and economical to produce and are quickly and easily assembled. The bracket member is mounted upon the supporting plate; the face plate secured in position; and the dog mounted on its supporting disk is introduced through the hollow stud and retained in position by the engagement of its supporting disk with the 15 hooked lug.

I have illustrated my improvements as I have embodied them in supports for the tops of children's carriages. My improvements may, however, be readily adapted to other 20 uses, such, for instance, as windshields, but I have not illustrated such an adaptation as I believe the disclosures made will enable those skilled in the art to which my invention relates to embody or adapt the same as 25 may be desired.

Having thus described my invention, what I claim as new and desire to secure by Letters Patent is:

1. In a structure of the class described, 30 the combination of a supporting plate having hook-like lugs on its inner side and a hollow pivot stud on its outer side formed integrally therewith, a bracket member mounted on said stud, the end of said stud 35 being spun over said bracket member as a retaining means therefor, said bracket member being provided with a series of holes disposed concentrically of its pivot, a face plate for said bracket member having an opening therein aligned with said stud, a dog disposed through said hollow 40 stud and face plate and provided with a cap-like finger piece and with a forwardly turned engaging portion reciprocating through said supporting plate to coat with the holes in said bracket member when brought to alignment therewith by the adjustment of said member on its stud, said face plate constituting a stop for said dog, 45 a supporting disk for said dog having parts engageable with said lugs on said supporting plate by a rotative movement of the disk, and a spring arranged on said dog between its finger piece and said disk.

2. In a structure of the class described, 50 the combination of a supporting plate having hook-like lugs on its inner side and a hollow pivot stud on its outer side formed integrally therewith, a bracket member 55 mounted on said stud, the end of said stud being spun over said bracket member as a retaining means therefor, said bracket member being provided with a series of holes disposed concentrically of its pivot, a dog disposed through said hollow stud and

provided with a finger piece and with a forwardly turned engaging portion reciprocating through said supporting plate to coat with the holes in said bracket member when brought to alignment therewith 70 by the adjustment of said member on its stud, a supporting disk for said dog having parts engageable with said lugs on said supporting plate by a rotative movement of the disk, and a spring arranged on said dog between its finger piece and said disk. 75

3. In a structure of the class described, 80 the combination of a supporting plate having lugs on its inner side and a hollow pivot stud on its outer side, a bracket member mounted on said stud, a face plate for said bracket member having an opening therein aligned with said stud, a dog disposed through said hollow stud and face plate and provided with a cap-like finger piece and having a detent reciprocating through said supporting plate to engage said bracket member, a supporting disk for said dog engageable with said lugs on said supporting plate, and a spring arranged on said dog 85 between its finger piece and said disk. 90

4. In a structure of the class described, 95 the combination of a supporting plate having lugs on its inner side and a hollow pivot stud on its outer side, a bracket member mounted on said stud, a dog disposed through said hollow stud and face plate and provided with a finger piece and having a detent reciprocating through said supporting plate to engage said bracket member, a supporting disk for said dog engageable with said lugs on said supporting plate, and a spring arranged on said dog between its finger piece and said disk. 100

5. In a structure of the class described, 105 the combination of a supporting plate having lugs on its inner side, a bracket member pivotally mounted on the outer side of said plate, a dog disposed through said plate and bracket member axially of the pivot, 110 said dog being provided with a cap-like finger piece, a dog supporting member in which the said dog is reciprocatingly mounted, said supporting member being engageable with said lugs on said supporting 115 plate, and a spring disposed on said dog between said cap and supporting member.

6. In a structure of the class described, 120 the combination of a supporting plate having hook-like lugs on its inner side and a hollow pivot stud on its outer side, a bracket member mounted on said stud, a dog supporting disk engageable with said lugs on said supporting plate by a rotative movement of the disk, and a dog mounted on 125 said disk to coat with said bracket member and disposed through said hollow stud.

7. In a structure of the class described, 130 the combination of a supporting plate, a bracket member pivotally mounted on the

outer side of said supporting plate, a dog supporting member disposed on the rear side of said supporting plate and engageable therewith by a rotative movement, and
5 a dog mounted thereon to coact with, and disposed axially of said bracket member.
In witness whereof, I have hereunto set

my hand and seal in the presence of two
witnesses.

CHARLES A. LINDBERG. [L.s.]
